UNITED STATES PATENT OFFICE

139,258

DESIGN FOR A SWEATER

Max Rubenstein, New York, N. Y.

Application August 29, 1944, Serial No. 115,122

Term of patent 3½ years

(Cl. D3—4)

To all whom it may concern:

Be it known that I, Max Rubenstein, a citizen of the United States of America, residing in city of New York, county of New York and State of New York, have invented a new, original, and ornamental Design for a Sweater, of which the following is a specification, reference being had to the accompanying drawing, forming part thereof.

Fig. 1 is a front view of a Sweater showing my new design.

Fig. 2 is a rear view thereof.

I claim:

The ornamental design for a sweater, substantially as shown.

MAX RUBENSTEIN.
